UNITED STATES PATENT OFFICE

152,965

DESIGN FOR A BUILDING

George K. Harris, Jr., Detroit, Mich., assignor to
National Steel Corporation, a corporation of
Delaware

Application June 27, 1947, Serial No. 139,969

Term of patent 14 years

(Cl. D13—1)

To all whom it may concern:

Be it known that I, George K. Harris, Jr., a citizen of the United States of America, residing at Detroit, in the county of Wayne and State of Michigan, have invented a new, original, and ornamental Design for Buildings, of which the following is a specification, reference being had to the accompanying drawing, forming part thereof.

Figure 1 is a perspective view of the building showing my new design;

Figure 2 is a front view of the building; and

Figure 3 is a rear view of the building; and
Figure 4 is an end view of the building.

I claim:

The ornamental design for a building, as shown.

GEORGE K. HARRIS, JR.
